UNITED STATES PATENT OFFICE

2,607,835

HIGH WATER SIGNAL

Bernard E. Bonar, El Paso, Tex.

Application June 26, 1950, Serial No. 170,441

9 Claims. (Cl. 177—311)

1

This invention relates to a signalling device primarily designed for use on railroads, highways, rivers, bridges or levees, and other places where flood water would be a menace or dangerous to life and property.

An important object of this invention is to provide a high water signal comprising a housing, a signal mounted on said housing, a float mounted for vertical movement in said housing, means actuated by the upward movement of said float for rotating said signal from a non-danger to a danger signifying position, and means for lockingly retaining said signal in the danger signifying position.

Yet another object of this invention is to provide a high water signal of the character described where the signal includes a panel having non-danger and danger-signifying positions, a light mounted on the signal adjacent the panel, and switch means in the housing operatively connected to the light and actuated by the upward movement of the float to energize the light and at the same time rotate the panel from the non-danger to the danger-signifying position.

These, together with various ancillary objects and features of the invention which will later become apparent as the following description proceeds, are attained by the device, a preferred embodiment of which has been illustrated by way of example only in the accompanying drawings, wherein:

Figure 1 is a perspective view of the signal;

Figure 2 is a vertical sectional view through the signal, parts being broken away to show details of construction;

Figure 3 is a sectional view taken substantially on the plane of section line 3—3 of Figure 2;

Figure 4 is a sectional view taken substantially on the plane of section line 4—4 of Figure 2;

Figure 5 is a sectional view taken substantially on the plane of section line 5—5 of Figure 2;

Figure 6 is a fragmentary perspective view of a detail of construction;

Figure 7 is a perspective view of the latch bar;

Figure 8 is a fragmentary top plan view of another detail of construction;

Figure 9 is a fragmentary vertical sectional view through the signal rod locking device; and

Figure 10 is a perspective view of the signal rod guide collar.

Specific reference is now made to the drawings. In the several views in the accompanying drawings and in the following specification simi-

2

lar reference characters indicate corresponding elements throughout.

The present device is generally indicated at 10 and includes a housing which may be of any desired shape but preferably rectangular and including side members 12 and 14 to the top and bottom of which are secured by welding or riveting angle irons 16 and 18 respectively. The side members 12 and 14 are themselves angle irons to which are secured a plate 20 adjacent the upper end of the housing and a plate 22 adjacent the lower end of the housing and extending centrally thereof for a purpose later to appear. Appropriately secured to the upper angle member 16 is a substantially rectangular frame member 24 while appropriately secured to the lower angle member 18 is a further substantially rectangular frame member 26.

Appropriately secured as by headed bolts and nuts 28 to the top and bottom angle members 16 and 18 as well as to the rectangular frames 24 and 26, are foraminous members or screens 30, four screens being provided so that the housing, in effect, has a perforated bottom wall as shown in Figure 3, a perforated rear wall as shown in Figure 2, and perforated side walls as shown in Figure 1. The screens are required to permit water to enter the housing and actuate the float which will be described hereinafter.

The front wall of the housing constitutes a solid door 32 having a handle 34, the door being hinged as at 36 to the bottom rectangular frame member 26. The upper wall of the housing constitutes a pair of doors 38 and 40 hinged as at 42 to the upper rectangular frame member 24. The frame member 24 includes a collar 44 that journals a latch rod 46 which extends across the door 40 and may be slid into engagement with a hasp or keeper 48 secured adjacent the top upper end of the front door 32 as shown clearly in Figure 1. Secured to the pivoted or hinged doors 38 and 40 at their point of juncture is a split collar 50 which slidably receives a signal rod 52 upon which is secured a preferably circular panel 54, the opposite faces of which panel will contain a danger-signifying color such as red. The panel has a certain thickness and the peripheral edge thereof is uncolored and will constitute a non-danger signifying position. Above the panel the rod mounts four lights 56, two in a plane with the panel and two in a plane perpendicular to the plane of the panel. The latter two include red lenses and the former two green lenses.

Secured by appropriate clamps 58 to the interior plates 20 and 22 are collars 60 to the in-

terior of which are secured appropriate bearings 62 which slidably journal a shaft 64 to the bottom of which is secured as at 66 a substantially rectangular float 68 which is preferably divided into compartments by means of appropriate partitions 70. The upper free end of the shaft 64 includes a knob 72 for a purpose later to appear. When the housing is placed on an appropriate site and flood waters enter the housing through the perforated walls thereof, the float and float 10 supporting rod 64 are lifted upwardly, and a means is provided in the present signal for rotating the panels 54 from non-danger to the danger-signifying position and for actuating the signal light 56 at the same time, which means 15 will be clearly described hereinafter.

Secured by means of an appropriate arcuate clamp 74 to the upper plate 20 is a guide collar 76, see Figures 5, 6 and 10, which guide collar includes a spiral slot 78 and a level seat portion 20 80 as well as an upper closure ring 82. The signal rod 52 is really a hollow rod which is secured within a short tubular member 84 which is vertically slidable within the slotted guide collar 76 as shown clearly in Figure 5. Secured to the signal rod 52 as at 86 is a laterally extending pin 88 which extends through the spiral slot 78 and also through a rectangular opening 90 in the support plate 20. The lateral pin 88 normally seats in the level seat portion 80 of the spiral slot 78 and is retained in a more or less fixed, non-rotative position.

A releasable latch bar 92 is provided which is pivoted intermediate its ends as at 94 to the support plate 20. The latch bar 92 includes a flat upper surface 96 and an undersurface which is slotted or grooved as at 98 to slidably receive the knob 72 of the float shaft 64. The end of the latch bar 92 adjacent the pivot 74 includes a notch 100 normally receiving the laterally extending pin 88 and an enlarged shoulder 102 having a cam surface 104 rising from the notch 100.

Appropriately secured to the support plate 20 above the latch bar 92 is an enclosed housing 106 carrying a toggle switch 108 which rests upon the upper flat surface 96 of the latch bar 92 and which is appropriately and operatively connected by means of conductor wires 110 to the signal light 56, it being understood that the wires extend through the hollow signal rod 52. Thus, when flood waters enter the housing through the perforated walls and lift the float 68, the knob 72 at the upper end of the float shaft 64 will slide to the right of Figure 2 within the slot or groove 98 and pivot the latch bar 92 so that the notched end 100 thereof releases the lateral pin 88 carried by the signal rod 52. As the latch 92 pivots, the cam surface 104 of the enlarged shoulder 102 pushes against the lateral pin 88 and urges it out of the level seat portion 80 of the spiral slot 78, so that the pin spirals down the slot 78, and in so doing the panel 54 rotates from the non-danger position to the danger-signifying position. At the same time, the flat surface 96 of the latch bar 92 pushes upwardly on the toggle switch 108 to energize the signal light 56.

As will be seen clearly in Figures 2 and 9, an arcuate clamp 112 embraces a tubular member 114 and secures the same to the bottom supporting plate 22 within the housing. A collar 116 is 70 suitably secured to the bottom end of the signal rod 52 and is slidably received within the tubular member 114, the bottom free end of the rod 52 including a flanged bearing 118. The bearing is secured to the rod 52 and collar 116 by means of 75

cross pin 120. Eccentrically pivoted in the bearing as at 122 is a latch or hook 124 which extends through a beveled aperture 126 in the horizontal leg portion of the angle plate 22. Thus when the pin 88 spirals downwardly in the slot 78 of the guide collar, the signal rod 52 moves downwardly and the pivoted latch or hook 124 moves through the aperture 126, and because of its eccentric mounting on the bearing 118, will engage the plate 22, as shown in Figure 9, and prevent upward movement of the signal rod 52 retaining the panel 54 in its danger-signifying position as well as keeping the signal lights 56 on until the entire signal apparatus is reset by hand.

From the above description it will be seen that when the signal apparatus is placed on a proper site, flood waters will actuate the float and cause the signal lights 56 to go on while the signal panel 54 will rotate to a danger-signifying position there to be retained by the hook or latching mechanism 122, 124, 126. To reset the signal apparatus, the doors 32, 38 and 40 are opened, the toggle switch 108 is flipped downwardly to put out the lights 56, the hook or latch 124 is released by hand, and the rod 52 is pushed upwardly until the lateral pin 88 re-engages the notch 100 in the latch bar 92. It should be remembered that when the signal is set in position alongside a railroad track, steel door 32, panel 54 and red reflector lights 56 are parallel with the track. The green reflector lights 56 are facing lengthwise with the track and trains approaching from either direction would get a clear signal. When flood waters get high enough to operate the signal, the panel and lamps will make a quarter turn and the red reflector lights and opposing red panel faces become exposed to the approaching trains.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A high water signal comprising a housing having perforate side walls and a top wall, a signal panel mounted on a rod extending through said top wall, a float carried on a shaft slidably mounted in said housing, guide means in said housing slidably receiving said signal rod, a lateral pin carried by said rod and extending through said guide means, and latch means pivoted in said housing and normally engaging said pin to retain said signal panel in a non-danger signifying position, said latch means being actuated by said shaft upon upward movement of said float to release said pin and a spiral slot engaging said lateral pin to rotate said signal rod to a danger-signifying position.

2. The combination of claim 1 wherein said guide means includes a collar having a spiral slot receiving said lateral pin.

3. The combination of claim 2 wherein said latch means includes a bar pivoted for vertical movement intermediate its ends, one end of said bar including a notch receiving said lateral pin.

4. The combination of claim 3 wherein said

bar includes an elongated slot, said shaft including a knob slidably received in said slot, said latch bar including a cam adjacent said notch adapted to bear against said lateral pin and urge it downwardly in said spiral slot upon downward pivotal movement of said notch end of said latch bar.

5. The combination of claim 1 and a light mounted on said signal rod, and switch means mounted in said housing operatively connected to said light and actuated by said latch means to energize said light after predetermined upward movement of said float shaft.

6. The combination of claim 1 and means for lockingly retaining said signal in the danger-signifying position, said means including a frame member in said housing having an aperture therethrough and a hook pivoted to the lower end of said signal rod adapted to pass through said aperture and engage said frame member to prevent upward movement of said signal rod.

7. A high water signal comprising a water pervious housing, a float shaft slidably mounted in said housing, a float secured at the end of said shaft, a latch bar pivotally mounted on said housing, said bar having a longitudinal groove therein, said shaft including a knob slidably received in said groove, a toggle switch mounted in the path of said bar for actuation thereby, a signal rod, said rod being vertically slidable, a laterally extending pin secured to said rod, a spiral slot adjacent said rod, said pin extending through said slot, means on said latch bar engaging said pin for maintaining said rod in elevated position, said latch bar releasing said pin into contact with said spiral slot to rotate said rod, a signal device mounted on said rod.

8. A high water signal comprising a water pervious housing, a float shaft slidably mounted in said housing, a float secured at the end of said shaft, a latch bar pivotally mounted on said housing, said bar having a longitudinal groove therein, said shaft engaging the groove in said

bar, a toggle switch mounted in the path of said bar for actuation thereby, a signal rod, said rod being vertically slidable, a spiral slot adjacent said slot, a laterally extending pin secured to said rod, said pin extending through said slot, means on said latch bar engaging said pin for maintaining said rod in elevated position, pivotal movement of said latch bar releasing said pin for sliding motion in said slot for rotating said signal rod, a signal mounted on said rod.

9. A high water signal comprising a water pervious housing, a float shaft slidably mounted in said housing, a float secured at the end of said shaft, a latch bar pivotally mounted on said housing, said bar having a longitudinal groove therein, said shaft including a knob slidably engaging the groove in said bar, a toggle switch mounted in the path of a guide collar about said rod, said bar for actuation thereby, a signal rod, said rod being vertically slidable, a spiral slot in said collar, a laterally extending pin secured to said rod, said pin extending through said slot, means on said latch bar engaging said pin for maintaining said rod in elevated position, pivotal movement of said latch bar releasing said pin, said pin rotating said signal rod, a signal lamp mounted on said signal rod.
